CLAIM

The ornamental design for a fishing lure, substantially as
shown and described.

DESCRIPTION

FIG. 1 is a side elevational view of a fishing lure showing
my new design, the opposite side being a mirror
image thereof;

FIG. 2 is a top plan view thereof, the bottom being a
mirror image thereof;

FIG. 3 is a left end view thereof; and

FIG. 4 is a right end view thereof.

FIG. 1

FIG. 2

FIG. 3

FIG. 4
